UNITED STATES PATENT OFFICE.

MASON B. GIBERSON, OF DETROIT, MICHIGAN, ASSIGNOR TO MONARCH STEEL CASTINGS COMPANY, OF DETROIT, MICHIGAN, A CORPORATION OF MICHIGAN.

DUST-COLLECTOR FOR GRINDERS.

1,094,553.

Specification of Letters Patent. Patented Apr. 28, 1914.

Application filed October 13, 1913. Serial No. 794,997.

To all whom it may concern:

Be it known that I, MASON B. GIBERSON, a citizen of the United States of America, residing at Detroit, in the county of Wayne 5 and State of Michigan, have invented certain new and useful Improvements in Dust-Collectors for Grinders, of which the following is a specification, reference being had therein to the accompanying drawings.

10 The invention relates to grinding machines of that type in which the grinder-wheel is mounted upon a flexible arm, carrying the driving connections, which permits of its being adjusted in various positions in 15 relation to the work.

It is the object of the invention to provide such a grinder with dust-collecting means which will not in any way interfere with the freedom of adjustment.

20 In the drawings: Figure 1 is a perspective view of the grinder; Fig. 2 is a sectional side elevation of the grinder-wheel and dust-collecting hood; Fig. 3 is a plan view thereof; and Fig. 4 is a plan of the jointed arm 25 of the grinder-frame, showing the connection to the dust-removing tool.

In the present state of the art, grinder-wheels for use in the hand-finishing of castings and for similar purposes have been 30 mounted upon universally-jointed frames, which also carry the driving belts. It is also common with stationary grinders to inclose the wheel by a hood for collecting the dust, which latter is drawn away through 35 a conduit by suction. With my improved construction, I have provided a flexibly-mounted grinder-wheel with a dust-collecting hood and exhaust conduit, without interfering with the flexibility of the frame, the 40 specific construction being as follows:

A is the grinder-wheel, mounted upon an arbor B, journaled in bearings C upon a bifurcated frame D. This frame D is connected with an arm E extending to a bifurcated frame or yoke F, which in turn is hinged to a corresponding yoke G connected to a vertical arm H, having a yoke I hinged to a stationary bracket J. The arms E and H each have a swiveled connection with one 50 of the yokes to which they are attached, thereby providing for a universal movement of the grinder-wheel A.

To collect the dust from the grinder, the wheel A is provided with a hood K, preferably formed integral with the yoke frame D

and provided with a detachable extension portion K', which may be removed for insertion of the grinder-wheel. The arms E and H are formed of tubes and the former is connected at its outer end with the hood 60 K, while its rear end has a swiveled engagement with the yoke frame F. The tube also preferably projects beyond the swiveled bearing into the space within the yoke and engages a nipple L, which is non-rotatively 65 connected to the yoke frame and is coupled by a flexible conduit M with a corresponding nipple at the end of the arm H. Thus the flexing of the hinge connection between the yokes F and G is not interfered with, and a 70 continuous conduit for the passage of the dust is maintained by the tubes E and H and connecting flexible conduit M. A similar flexible connection is formed between the upper end of the tube H and the stationary 75 exhaust conduit.

The grinder-wheel is driven by the usual belt-and-pulley drive connection indicated at N, and to permit of tightening the belts when they become loose from stretching, an 80 adjustment is provided for the length of the arms E and H. This is preferably formed by connecting the nipple L with the yoke frame F by bolts O having nuts P which when adjusted will move the nipple and tubular arm outward.

With the construction as described, when suction is placed upon the exhaust conduit, an air current will be drawn through the hood, tubular arms E and H and their connecting flexible conduits, to carry away the 90 dust from the grinder.

As the conduits are formed through the swiveled arms E and H, and as the flexible connections between these conduits also permit of swiveling, it is obvious that the freedom of movement of the jointed frame is not 95 in any way impaired.

What I claim as my invention is:

1. The combination with a grinder-wheel, 100 of a hood for inclosing said wheel, a jointed frame on which said wheel and hood are mounted, and an exhaust conduit leading from said hood through said jointed frame and permitting the flexing of the latter.

2. The combination with a grinder-wheel, 105 of a hood inclosing said wheel, a jointed frame on which said wheel and hood are mounted, including a plurality of pivotally-connected yoke frames, and tubular connect-

105

110

ing arms having a swiveled connection with said yokes, forming an exhaust conduit connected with said hood.

3. The combination with a grinder wheel, 5 of a hood for inclosing said wheel, a yoke frame on which said hood and wheel are mounted, a tubular arm extending from said yoke frame and connected with said hood, a hinged yoke at the opposite end of said 10 tubular arm, having a swiveled connection therewith, and a flexible conduit connected with said tube within said yoke.

4. The combination with a grinder wheel, 15 of a hood for inclosing said wheel, a yoke frame on which said hood and wheel are mounted, a pair of hinged yoke frames, tubular arms connected respectively to said hinged yoke frames, one of said arms being connected at its opposite end to the yoke 20 frame supporting said grinder wheel and to the hood thereof, and a flexible conduit connecting said tubular arms, permitting of the hinging or swinging movement of said yoke frame.

25 5. The combination with a grinder-wheel of a hood for inclosing said wheel, a yoke frame on which said grinder-wheel and hood are mounted, a tubular arm connected with said hood and yoke-frame, hinged yokes, 30 one member being swiveled to said tubular arm, and a flexible swiveled connection between said tubular arm and a conduit mounted on the other of said hinged yokes.

6. The combination with a grinder-wheel 35 of a yoke in which said wheel is mounted, a

hood for inclosing said wheel formed integral with said yoke, and a tubular arm supporting said yoke and forming a conduit connected with said hood.

7. The combination with a grinder-wheel 40 of a hood for inclosing said wheel, a yoke frame on which said hood and wheel are mounted, a second yoke frame, a tubular arm connected to said first yoke frame and swiveled in said second yoke frame, a belt- 45 and-pulley drive connection extending between said yoke frames, and means for adjusting said tubular arm longitudinally in its swiveled bearing to take up slack from said drive-belt connection.

8. The combination with a grinder-wheel 50 of a hood for inclosing said wheel, a tubular arm extending from said hood, a hinged yoke with which said tubular arm has a swiveled engagement, the end of said arm 55 projecting within the yoke, a flexible conduit, a nipple for connecting said flexible conduit with the end of said tubular arm, a belt-and-pulley drive connection extending between said grinder-wheel and hinged yoke, 60 and adjustable connecting means between said nipple and hinged yoke for lengthening said tubular arm to take up slack in said belt-and-pulley connection.

In testimony whereof I affix my signature 65 in presence of two witnesses.

MASON B. GIBERSON.
